WOOD JOINT

Elwood I. Tripp, Seattle, Wash., assignor to I. F. Laucks, Inc., Seattle, Wash., a corporation of Washington

Application April 4, 1935, Serial No. 14,620

4 Claims. (Cl. 20—92)

This invention relates to wood joints, to box ends and the like comprising such joints, and to methods for the formation thereof.

An object of the invention is the provision of a wood joint whereby two pieces of wood will be effectively held together and which may be readily formed.

Another object is to provide a simple and effective method of providing such a joint.

10 Another object is to provide a composite box end and the like wherein the parts are securely held together and which may be formed with especial ease.

Still another object is to provide an improved 15 method for the formation of box ends and like articles.

Other objects of the invention will in part be obvious and will in part appear hereinafter.

The invention accordingly comprises the several steps and the relation and order of one or 20 more of such steps with respect to each of the others, and the article possessing the features, properties, and the relation of elements, which are exemplified in the following detailed disclosure, and the scope of the application of which will be indicated in the claims.

For a fuller understanding of the nature and 25 objects of the invention reference should be had to the following detailed description taken in connection with the accompanying drawing, in which:

Figure 1 is a perspective view of a double-end blank for box ends embodying the invention;

Fig. 2 is an end view of a box end formed 30 therefrom;

Fig. 3 is an enlarged view illustrating a form 35 of wood joint embodying the invention and comprised by the various forms of construction exemplified;

Fig. 4 shows one of the pieces of the wood joint 40 of Fig. 3 ready for joining;

Fig. 5 shows the other piece of the wood joint 45 of Fig. 3 ready for joining;

Fig. 6 shows a manner in which a wood joint 50 such as contemplated by the invention may be utilized in flooring;

Fig. 7 shows a manner in which a wood joint 55 such as contemplated by the invention may be utilized in furniture framework; and

Fig. 8 shows the manner in which a wood joint 60 such as contemplated by the invention may be utilized in doors.

While a wide variety of methods for the formation of wood joints have been proposed, and 65 wood joints of many different characters have

been devised, such methods have proved cumbersome or inefficient and such joints have been subject to a variety of drawbacks including insufficiency of the union, tendencies toward breakage and deformation, unsightliness, expense of formation, etc. The result has been that although the formation of box ends by joining together small pieces of lumber is common practice, supplementary means such as metal clips are ordinarily relied upon to hold the parts firmly together. Again in the formation of composite flooring strips and in the union of pieces of wood for making furniture, doors, etc., various complicated structures and procedures have been necessary in order to secure a joint which is adapted for various of the uses to which such articles are put.

With the foregoing and other considerations in view, the invention contemplates the provision of a simple, firm, permanent and attractive 20 wood joint which can be formed with extreme ease, of box ends utilizing such joints, and of simple and effective methods for the formation of such joints and of various articles embodying the same.

Among the features of the invention are the use of a tongue-and-groove formation of a character such that the parts may be readily put together and securely held in place, the avoidance of uneven distribution of the glue, the application of glue only at the tongue-and-groove portion of the adjoining surfaces, the provision of means to prevent spreading of the sides of the groove and to relieve strain on tongue, and the provision of various combinations of elements 30 and steps which result in a greatly improved product and a greatly simplified method of formation.

One embodiment of the invention in its various aspects is exemplified in the showing of Figs. 1 through 6. In Fig. 1 there is illustrated a blank adapted for the formation of box ends and comprising pieces of scrap lumber 10, 11, 12 and 13 which have been joined together in accordance with the invention. As exemplified, the piece 10 45 has been formed with a pair of grooves 14—14 along one of its narrow side surfaces and each of the pieces 11, 12 and 13 have been formed with tongues 15—15 on one of the narrow end surfaces of each. As will be observed, the width of each groove 14 increases outwardly,—at a 20° angle in the present instance,—and the width of each tongue correspondingly decreases outwardly, so that the tongues may be moved into the grooves with the utmost ease, and so that glue 55

applied to one or the other of these interfitting portions will not be scraped off as the two are, 5 pressed together. As will also be apparent from Figs. 3, 4, and 5, the surface of the grooved piece 10 recedes, as shown at 16, at each side of the groove and the surface of each tongue-carrying piece 15 protrudes, as shown at 17, correspondingly at each side of the tongue. Thus, spreading of the sides of the groove is prevented, and at the same 20 time the strain on the tongue which normally results from lateral stresses is considerably relieved, since bending stresses will give an equalized strain throughout the joint. While in the preferred construction the walls of the groove 25 meet the receding surfaces 16 in an acute angle; it will be understood that in various instances the receding and protruding surfaces, if utilized, may be spaced from the groove and tongue respectively, and also that they may, if desired, terminate short of the face of the board or the proposed saw-line. Firm interlocking of the parts, 30 and relief of strain is thus given by an exceedingly simple means which requires no additional wastage of wood and no especially complicated sawing operations. In this connection it is to be noted that the angularity of the walls of the tongue and groove should not be large, as increasing angularity will result in decreased wedging action and consequently in less mechanical 35 strength in the joint and insufficient tendency to hold the pieces together during the setting of the glue.

In the formation of the joint, glue may be applied to either the tongue or the groove, but is 40 preferably applied in the groove as indicated at 35 18 (Fig. 4) and the pieces pressed together. As above pointed out, the glue will not be scraped off the side walls of the groove, or of the tongue if applied thereto, during this movement. No glue 45 is applied to the portion beyond the groove so that the presence of glue adjacent to the faces of the pieces joined where it will be unsightly, or to a point between pairs of tongues and grooves where the double-end blank is to be re-sawn, will be avoided. Since many glues have a dulling effect 50 on saws, this feature is particularly advantageous in making the box ends and other procedures wherein re-sawing of the pieces is contemplated.

It will be apparent that the provision of a 55 joint such as exemplified, not only results in the formation of a particularly strong final structure, but also permits the bonding time to be reduced and the article to be handled much earlier than would otherwise be the case.

In the formation of a box end from a double-end blank such as shown in Fig. 1, it is only 60 necessary to saw the double-end blank throughout its extent on a plane as indicated by the dot-and-dash line 20, there being produced two box 65 ends, one of which is illustrated in Fig. 2. As will be apparent, a box end may be formed directly by joining relatively narrow pieces of lumber; and three, four or more box ends may be sawed from a single blank depending upon the thickness of 70 the stock used and the thinness of the box ends desired, it being only necessary to provide interfitting portions for each of the box ends to be sawed from the multiple-end blank. If desired, each box end or other final article may embody 75 a plurality of interfitting portions on each end glued, but ordinarily this is an unnecessary complication of the structure and of the procedure. In the formation of box ends or other articles, pieces of scrap lumber may be joined in any desired manner depending upon the size of the

pieces and the structure to be formed. For instance, the group of pieces 11, 12 and 13 may be replaced by one, two, four, or any other desired number of pieces, the portion 10 may be replaced by a plurality of pieces and the portions may be 5 variously arranged as may be necessary or desirable to fit them in properly. Ordinarily when a single piece extending across the blank, such as the piece 10, is utilized, it is unnecessary to provide any special joint between the other pieces, 10 such as 11, 12 and 13, although glue would be applied between their flat surfaces in most instances. However, in instances where a particularly strong and attractive product is desired, a 15 joint such as contemplated by the invention may be provided between the piece 12 for instance and the pieces 11 and 13. Desirably the grain of the wood may extend along the pieces as indicated in the drawing, so that the grain of the various joined pieces runs in different directions, but that 20 nevertheless all the tongues run in the direction of the grain. In a construction such as exemplified the provision of the protruding surfaces 17 in the end grain assists in overcoming the tendency 25 of the side grain at the exterior of the grooved pieces to curl up. If tongues are formed to join the piece 12 to the pieces 11 and 13, the tongues should be formed on the piece 12 for the same reason and the pieces 11 and 13 should be grooved, 30 the tongues being formed in end grain in all 35 cases, as will be apparent from Fig. 1.

As will be apparent a joint such as contemplated by the invention may be utilized in uniting a wide variety of types of construction. For 40 example flooring boards may readily be formed 35 of random short lengths as indicated at 21 and 22 (Fig. 6). The otherwise waste pieces may be matched and glued in the factory to make lengths convenient for laying. Tongue and groove flooring may also be end matched by the provision of 45 a similar joint with or without gluing. Again, furniture framework may be formed by gluing the pieces in accordance with the invention in the manner indicated for example in Fig. 7 where the piece 23 is grooved and the tongued piece 24 50 fitted against it, or doors having joints formed as above indicated may be constructed in a manner such for example as shown in Fig. 8, wherein the pieces 25 and 26 are grooved and cut away 55 to receive tongued pieces such as shown at 27, 28 and 29, and the panels 30.

As will be apparent, in all the structures exemplified, there are utilized joints such as exemplified in Fig. 3 and embodying the various 60 features of the invention, but the utilization of constructions embodying only one or more of features disclosed have many advantages for a variety of purposes. However, in the preferred 65 and exemplified forms each joint includes a wedge-shaped tongue 15 cut in end grain, as illustrated, and glued in the wedge-shaped groove 14 and unglued receding portions 16 and protruding portions 17.

It will be appreciated that some glue may work 70 out beyond the edges of the groove; and that while the term "unglued" is utilized for the sake of facility of expression to define certain of the surfaces, it is to be understood that this term is used as referring to surfaces which do not carry 75 any material amount of glue, at least at such portions thereof where glue is undesirable.

Since certain changes in carrying out the above 80 method, and certain modifications in the article 85 which embody the invention may be made without

departing from its scope, it is intended that all matter contained in the above description or shown in the accompanying drawing shall be interpreted as illustrative and not in a limiting sense.

5 The invention claimed is:

1. A wood joint comprising juxtaposed pieces of wood having glued closely-interfitting portions of tongue and groove formation, unglued surfaces disposed laterally of said tongue and groove and extending to the edges of the pieces, and sharp bends between the tongue and the groove and the unglued surfaces.

2. A wood joint comprising juxtaposed pieces of wood, one having a tongue and the other a groove, said tongue and groove being glued together and said pieces having unglued surfaces disposed laterally of said tongue and groove and extending to the edges of the pieces, and sharp bends between the tongue and the groove and the unglued surfaces, said tongue and groove being of wedge-shaped formation, and a surface of the grooved piece receding at each side of the groove and a surface of the tongue-carrying piece protruding at each side of the tongue.

3. A box-end or the like, comprising a piece of wood one edge-surface of which forms an edge-surface of the article, and a plurality of other pieces of wood at least certain of which have an

edge-surface meeting the opposite edge-surface of the first-mentioned piece, the meeting edge-surfaces of said first piece and said certain of said pieces comprising a wedge-shaped tongue glued into a wedge-shaped groove and unglued 5 surface portions disposed laterally of said tongue and groove and extending to the edges of the pieces, there being sharp bends in the meeting surfaces between said tongue and groove and said unglued surface portions, and said unglued 10 surface portions being inclined laterally of said bends to protrude in the direction of said tongue and to recede in the direction of said groove.

4. The method of forming box-ends and the like which comprises forming the edge surfaces 15 of each of a plurality of pieces of wood to provide a plurality of spaced sets of closely interfitting portions adapted for wedging inter-engagement and with sharp bends on each side of the inter-engaging portions and laterally 20 disposed contacting surfaces between said sets and laterally beyond the same, applying glue only between said inter-fitting portions, assembling the pieces with said edge surfaces in engagement, and dividing the assembly on a plane 25 extending thru the unglued surfaces between the sets.
